DESIGN FOR A JEWELRY COMPONENT

Joseph Shore, Revere, Mass.

Application April 25, 1940, Serial No. 91,944

Term of patent 3½ years

To all whom it may concern:

Be it known that I, Joseph Shore, a citizen of the United States of America, residing at Revere, in the county of Suffolk, in the Commonwealth of Massachusetts, have invented a new, original, and ornamental Design for a Jewelry Component, of which the following is a specification, reference being had to the accompanying drawing, forming a part thereof.

I claim:

The ornamental design for a jewelry component, substantially as shown.

JOSEPH SHORE.
